UNITED STATES PATENT OFFICE.

JAMES HARDEN, OF NEW YORK, N. Y., ASSIGNOR TO THE ACHESON HARDEN COMPANY, OF NEW YORK, N. Y., A CORPORATION OF NEW JERSEY.

DESIGN FOR A HANDKERCHIEF, NAPKIN, OR SIMILAR ARTICLE OF MANUFACTURE.

61,036.

Specification for Design.

Patented June 6, 1922.

Application filed November 17, 1921. Serial No. 515,963. Term of patent 3½ years.

To all whom it may concern:

Be it known that I, JAMES HARDEN, a citizen of the United States, and a resident of the city of New York, borough of Manhattan, in the county and State of New York, United States of America, have invented a new, original, and ornamental Design for a Handkerchief, Napkin, or Similar Article of Manufacture, of which the following is a specification, reference being had to the accompanying drawing, forming a part thereof, wherein—

The figure represents my design as applied to a handkerchief.

My design may be applied to surface ornamentation in any form; as for instance, wallpaper, textiles or similar articles.

What I claim and desire to secure by Letters Patent is:

The ornamental design for a handkerchief, napkin, or similar article of manufacture substantially as shown and described.

JAMES HARDEN.
